UNITED STATES PATENT OFFICE.

ADOLPH F. FELLER, OF BERKELEY, CALIFORNIA.

AIR-COMPRESSOR.

1,110,123.

Specification of Letters Patent. Patented Sept. 8, 1914.

Application filed November 18, 1911. Serial No. 659,887.

To all whom it may concern:

Be it known that I, ADOLPH F. FELLER, a citizen of the United States, residing at Berkeley, in the county of Alameda and State of California, have invented certain new and useful Improvements in Air-Compressors, of which the following is a specification.

This invention relates to improvements in air compressors and motors for driving the same, and one of the novel features of the invention resides in a construction wherein the motor and compressor are combined in a single casing.

My invention also resides in certain novel features of construction embodied in the motor for driving the compressor, and further, in novel features of construction embodied in the compressor.

My invention will be more fully described in connection with the accompanying drawings and will be more particularly pointed out by the appended claims.

In the drawings:—Figure 1 is a view in side elevation of one embodiment of my invention showing a portion of the casing removed to disclose interior portions of the mechanism. Fig. 2 is a view in elevation showing a portion of the casing removed to disclose the compressor. Fig. 3 is a horizontal sectional view on line 3—3 of Fig. 2. Fig. 4 is an end view. Fig. 5 is a sectional view on line 5—5 of Fig. 1. Fig. 6 is a sectional view on line 6—6 of Fig. 1.

Like numerals of reference designate similar parts throughout the different figures of the drawings.

My invention will now be described in connection with the specific embodiment herein disclosed by the accompanying drawings but it will be understood that I do not wish to be limited to the precise construction shown except for such limitations as the claims may import.

As shown, 1 designates a casing having a compressor 2 and a pump chamber 3 divided by a partition 4. The sides of the casing are open and suitable journal plates 5 and 6 may be provided to close the sides of the casing and may be secured in any desired manner. Conveniently the plate 5 is provided with a bearing 7 in which is journaled one end of a main operating shaft 8. The other end of said shaft is journaled in a bearing 9 formed in the plate 6 and the

shaft may also have a bearing in the partition 4.

Any suitable form of packing may be provided to prevent communication between the compressor and pump chambers, 2 and 3 respectively, at the point where the shaft 8 passes through the partition 4. However, inasmuch as this is not a feature of my invention, the packing is not shown.

An idler shaft 10 is disposed in parallel relation with the shaft 8 and one of its ends is journaled in the casing, as at 11, and the other end is journaled in a bearing 12 in plate 6.

Referring now to the construction of the motor, the same consists as shown of two rotary turbine elements 13 and 14 having teeth or blades adapted for coacting mesh engagement. The width of the rotary elements 13 and 14 is sufficient to fill the pump chamber, transversely thereof, and the chamber is so proportioned that the peripheral portions of the teeth of the elements 13 and 14 engage the interior of the chamber with a tight working fit.

The pump chamber 3 is provided with an inlet 15, for the motive fluid, and I preferably provide deflecting means 16, which may be in the form of a transversely disposed member shown in Figs. 1 and 6, arranged to deflect the motive fluid toward the oppositely receding teeth or blades of the turbine elements 13 and 14. An outlet 17 is provided for the pump chamber 3, and if desired, arresting means 18 may be provided to prevent the turbine blades from carrying the outgoing fluid upwardly into the intake side of the elements 13 and 14. Segmental grooves 19 and 20 may be provided in the cover plate 6 and in the partition wall 4 respectively to permit the escape of motive fluid which is trapped by the turbine teeth or blades, and, in cases where steam is used, to prevent the formation of a vacuum.

It will be seen from the construction hereinbefore described, that each element 13 and 14 acts as a driving turbine element and notwithstanding the fact that the load is directly imposed upon the element 13, the element 14 will coact with the element 13, by reason of the mesh engagement, and will afford a working surface area to the motive fluid equal to the working area afforded by the element 13.

The compressor comprises a rotor 21

which is mounted upon the main operating or driving shaft 8 and which is reduced in diameter with respect to the internal diameter of the compressor chamber 2. It will 5 also be noted by reference to Fig. 2 that the shaft 8 is eccentrically disposed with respect to the chamber 2 and the proportions and arrangement are such that the rotor 21 engages the wall of the chamber 2 at one point there- 10 of. An air inlet 22 is provided and an outlet 23 also communicates with the chamber 2 and the inlet and the inlet and outlet open to the chamber 2 at points adjacent the point of contact of the rotor 21 with the chamber 2. 15 The rotor 21 is provided with a reduced journal 24 seated in a bearing 25 formed in the partition 4. The remainder of the body of the rotor 21, and the shaft 8 for a width equal to the width of the chamber 2, is 20 grooved or subdivided to provide a passage or slideway for vanes 26 and 27. The vanes 26 and 27 are normally displaced in opposite directions and toward the peripheral wall of the chamber 2 by means of one or more ex- 25 pansively acting springs 28 and the outer ends of the vanes 26 and 27 are provided with sockets 29 and 30 for receiving shoes 29' and 30', respectively. The shoes 29' and 30' have segmental oscillatable bearing 30 surfaces 30 and 34, respectively, which are formed complementary to the said sockets 29 and 30, respectively, and the outer bearing faces of said shoes are formed complementary to the internal periphery of said 35 casing 2. As indicated in dotted lines in Fig. 2, when the rotor 21 is turned, the shoes follow closely the internal periphery of the casing and oscillate back and forth at each revolution of the rotor. Corresponding 40 recesses 31 and 32 are provided in the periphery of the rotor 21, and at the extremities of the grooved portions thereof, to receive the shoes 29 and 30, respectively, as will be obvious by reference to Fig. 2. 45 The operation will be fully understood from the foregoing description but may be briefly recapitulated as follows:—Entrance of the motive fluid through the inlet 15 will drive the elements 13 and 14 in opposite di- 50 rections as indicated by the arrows and the motive fluid will be discharged through the

outlet 17. Operation of the elements 13 and 14 will drive the rotor 21 in the direction indicated by the arrow and assuming that the parts are in the position shown in Fig. 55 2, air will be drawn in the intake 22 behind the shoe 29. The right hand portion of the chamber will be filled with induced air whereas the vane 27 will be forcing the air in the left hand side of the chamber 2 outwardly through the outlet 23.

It will thus be seen that the action of the compressor is substantially continuous and that the action of the motor is substantially continuous, thereby providing a very effi- 65 cient action.

It will be understood that the compressor may be utilized for gases other than air and that any desired motive fluid may be utilized for the motor. 70

I claim:

A motor of the geared type comprising a casing and guide plates therefor, said plates having substantially flat inner surfaces, two intermeshing gears mounted within said 75 casing, said casing being provided with an inlet and an outlet on opposite sides of the point of contact between the teeth of said gears, a pair of baffles of similar shape disposed in front of said inlet and said outlet 80 respectively, and adapted to direct fluid onto the teeth of both of said gears equally, said baffles being provided with a pair of curved surfaces adapted to make rubbing contact with the ends of the teeth on each 85 of the gears, and said guide plates being provided with two pairs of segmental grooves one pair on each side of the line joining the centers of rotation of the two gears, each of said grooves extending from 90 a point on a line with the ends of the teeth of one of the gears near the line of connection between the centers of the gears to a point beyond said baffles and in free communication with either said inlet or said 95 outlet.

In testimony whereof I affix my signature in presence of two witnesses.

ADOLPH F. FELLER.
